UNITED STATES PATENT OFFICE.

JOHN FRANKLIN MACINDOE, OF PHILADELPHIA, PENNSYLVANIA, ASSIGNOR TO
FRANKLIN BRASS MANUFACTURING COMPANY, OF PHILADELPHIA, PENNSYLVANIA, A CORPORATION OF PENNSYLVANIA.

OILER.

1,290,618.

Specification of Letters Patent.

Patented Jan. 7, 1919.

Application filed August 6, 1917. Serial No. 184,575.

To all whom it may concern:

Be it known that I, JOHN FRANKLIN MACINDOE, a citizen of the United States, residing at Philadelphia, in the county of Philadelphia and State of Pennsylvania, have invented certain new and useful Improvements in Oilers, of which the following is a specification.

The object of my invention is the construction of an oiler or lubricator for elevator guide rails and the like, which will be simple and comparatively inexpensive to manufacture, durable in use, and which will not clog nor drip, and such other purposes as may hereinafter appear, and to that end consists in the novel features of construction, combination and arrangement of parts hereinafter described and claimed.

In the accompanying drawings, wherein the preferred embodiment of my invention is illustrated,

Figure 1 is a side view of the device,

Fig. 2 is a top view of the device,

Fig. 3 is a sectional view on line 3—3 of Fig. 2,

Fig. 4 is a plan view of the device on line 4—4 of Fig. 3,

Fig. 5 is a side elevation of a distributor,

Fig. 6 is a sectional view of the device showing a single distributor, instead of a plurality of distributors, and

Fig. 7 is a detail view on line 6—6 of Fig. 6.

Similar reference characters refer to similar parts throughout the drawings.

Elevator oilers employing fabric wicks as a means for conveying oil to elevator guide rails may be described as being of two types, viz: the straight capillary type and the capillary-gravity type.

In the former the wick contacts against the rail and as the oil is removed from the end of the wick by the mechanical action of the elevator, that is the movement of the elevator up and down the rail, the oil continues to rise. This method is more or less unsatisfactory as the pressure of the wick against the rail and its being moved at a rapid speed in contact, and the dust and dirt usually prevalent in elevator shafts, to a greater or lesser degree, causes the part of the wick bearing against the rail to become glazed, thereby interrupting the circulation of the oil from the lubricator to the rail,

making it necessary to either replace with new wicks, or to remove the glazed wick, and immerse it in kerosene, gasolene or some similar fluid to remove the hardened surface from the wick in order to make the lubricator again operative. As to the second type described as capillary-gravity, this type was designed to overcome the defective operation of the straight capillary type, and while the glazed wick defect has been corrected, another element of defectiveness is apparent, namely, the inability to control the flow of the oil causing a circulation of oil to the rail as long as any remains in the lubricator. This action occurs at all times, especially at increased temperatures, no matter if the car is running or at rest. It is therefore obvious that when the car is in the pit at night, Sundays and holidays, the oil continues to flow in proportion to the carrying capacity of the wicks, and trickles down the guide rails, not only wasting the oil, but making it necessary to employ drip pans, or placing bunches of waste to absorb the oil, the latter being, to a partial degree, an element of fire risk.

This present invention, known as the under-feed oiler, because of the position of the distributors, (being beneath the lubricant), is of the capillary-gravity type.

As capillary circulation cannot be controlled unless either the discharge end of the wick is disengaged from the rail or the submerged end is removed from the oil, I have designed the distributors in my lubricators to store the oil that has circulated during the idle periods of the elevator and apply this oil to the rail on the first trip the car makes out of the pit. The advantage of this being that I make good use of the oil that would have been wasted in other types of capillary-gravity oilers that do not provide storage type distributors.

Another feature of my device is the ability to use heavy oils or fluid grease and adjust a port so that the wick saturation can be maintained to a maximum that will not be affected by the low temperatures of winter or the heat of summer; this is an important feature as numerous freight elevators while loading are exposed to low temperatures in winter.

While it is admitted that the co-efficient of friction of oil is not as low as the co-

efficient of grease, and that the lubrication of vertical surfaces such as guide-rails of elevators is more difficult owing to the inability to efficiently use a circulating system 5 on account of the oil running down the surface, yet the construction of my lubricator is such that oil wastage is prevented, and that a maximum saturation of the wick is maintained, and that as the wicks which I 10 employ do not contact with the rail surfaces, and are concealed and protected from dust and dirt, it produces a lubricator having many points of superiority over the lubricators of the same type now in use.

15 Referring to the drawings the letter *a* represents a body, reservoir or receptacle for the oil, preferably of the design shown, secured to the elevator shoe in any suitable manner. As here illustrated by means of a 20 drilled pad *d* with the set screw *e* to any suitable attachment to elevator shoe.

Said reservoir *a* is provided with a suitable cover *b*, hinged as shown at *c* to permit of ready ingress and egress to the interior of 25 said reservoir.

A central distributor *f* is positioned equidistant between side distributors *g* and *g'* as shown, the three distributors being grouped within the under part of said reservoir *a*. 30 Said central distributor *f* is slidably mounted in pocket *h* recessed in under side of body *a*.

A spring *i* is provided between the rear wall *j* of pocket *h* and the rear part of said 35 distributor *f*, for the purpose of holding said distributor in contact with the rail *k* and allows for free movement thereof for any lateral motion of the elevator, and holds said distributor so that it will not leave its 40 contact with the rail in order that it may lubricate the face of said rail. Distributors *g* and *g'* are slidably mounted in the lower part of reservoir *a* as shown, directly opposite each other. They are provided, in 45 the same manner as the distributor *f*, with springs *m* and *m'* positioned as illustrated, the reservoir or body *a* being bulged as at *l* to provide spaces therefor, for the purpose of holding said distributors in contact with 50 the rail *k* and they allow for free movement thereof for any lateral motion of the elevator, and hold said distributors so that they will not leave their contact with the rail in order that they may lubricate the sides of 55 said rail.

Directly above pocket *h* an auxiliary pocket *n* is provided, as illustrated, in the under portion of the body *a* for the purpose of providing means of access for the wicks *o* to the distributors and for the purpose of 60 allowing adjusting space for the tube *p*.

These tubes *p* contain ports *q* drilled in a threaded portion of said tubes as shown, the opening being exposed to the oil reservoir *a* 65 when the tube is turned upwardly permit-

ting the oil to enter said port to increase the saturation of the wick or to permit the oil to run by gravity into the pockets *n*, thence to the distributors, if so desired. A metal strip *r* is employed to keep the wicks *o* taut. 70

Limit stops *s* are provided to prevent the distributors *g* and *g'* from being displaced when not in contact with the elevator rail.

Referring particularly to Fig. 5 of the drawings, showing a side elevation of the 75 distributor *f*, a bridge wall *t*, having a sloping surface, is provided as shown, the lower portion thereof terminating at the face of said distributor to permit the oil to flow to the guide rail without interruption. Said 80 bridge wall *t* also acts as a wall to the storage space *u*, but does not extend to the full height of the distributor *f* so that the oil can flow over the top of the bridge wall into the space *u* without flowing over the top of the distributor, as when the distributor *f* is in contact with the guide rail *k* the storage space *u* is directly under the reservoir outlet. Passages *v* are provided to drain the oil 85 that has been stored in space *u* permitting the oil to be applied to the rail as the elevator is in motion. Distributors *g* and *g'* have the same construction in this respect as distributor *f*. The wicks *o* extend from the bottom of the reservoir *a* upwardly and above 90 the surface of the oil into, down and through the internal tubes *p*, emerging from the lower end of said tubes into the pocket *n*, thence to the distributor as illustrated.

A slot *w* is provided in the upper end of 100 internal tube *p* to facilitate adjustment.

As described the distributors have a double feed, one being an inclined surface taking the ordinary wick delivery, the other comprising a passage or passages so formed as 105 to drain the surplus oil saved during idle periods and delivering same to the guide.

The wicks *o* are a fixed part of the construction and are not exposed to the dirt or dust, nor contacts with the rail, and are 110 therefore not an active working part; that is, the distributors can be replaced without having to use new wicks, or dismantling the wicks.

The distributors afford greater protection 115 to the elevator shoes by picking up the grit instead of riding over it—this reduces the wear of elevator shoes to a marked degree.

The ports *q* provided in the lower end of each tube *p* can be concealed by turning the tube downwardly, as they are drilled in the threaded portion of the tube, and when so concealed, make the operation strictly of the capillary gravity type using the lighter 120 grades of oil. The wicks *o* are mounted on metal strips, or on wire for ease of assembling and passed down through the cavity or pocket *n* provided immediately above each distributor pocket or cavity *h* for the delivery or discharge end of the wick, which 125 130

in practice comes to and lies at the outer portion of the upper pocket, permitting the oil to pass to the distributor.

The distributors provided are of a peculiar 5 and effective design, combining an immediate delivery of oil for each upwardly and downwardly movement of the car, and also a space for the storage or surplus oil gathered during the idle periods of the elevator.

10 Passages or channels are provided to convey to the rail the oil thus saved during said idle periods, thereby increasing the lubrication as compared with other types of oilers now in use.

15 In general practice one tube and one wick are provided for each surface, although a single wick and a single tube, as illustrated in Fig. 6, can be used for lubricating the front surface of the guide rail—a lesser degree of efficiency resulting.

20 I do not restrict myself to the exact details of construction, combination and arrangement herein set forth, it being obvious that minor variations thereof not involving 25 the exercise of invention may be made by the skilled mechanic, and such departure from what is herein described and claimed not involving invention I consider as within the terms and scope of my claims.

30 Having thus described my invention what I claim as new and desire to secure by Letters Patent is:

1. An oiler for elevator guide rails, comprising a reservoir to be carried by the elevator, distributors slidably mounted in the lower part of said reservoir and beneath the lubricant, means for holding said distributors in operative contact with the guide rail, internal tubes, wicks extending upwardly 35 from the bottom of said reservoir into, down and through said internal tubes, a pocket provided in the under portion of said oiler, said wicks emerging from said tubes into said pocket and thence to the distributors, and means carried by said internal tubes to increase the wick saturation.

2. An oiler for elevator guide rails, comprising a reservoir to be carried by the elevator, distributors slidably mounted in the lower part of said reservoir and beneath the lubricant, means for holding said distributors in operative contact with the guide rail, internal tubes, wicks extending upwardly 50 from the bottom of said reservoir into, down and through said internal tubes, a pocket provided in the under portion of said oiler, said wicks emerging from said tubes into said pocket and thence to the distributors, ports, drilled in the threaded portion of 55 said tubes, by means of which an increased saturation of said wicks may be had or heavier grades of oil may be used.

3. An oiler for elevator guide rails, comprising a reservoir to be carried by the elevator, distributors slidably mounted in the 60

lower part of said reservoir and beneath the lubricant, means for holding said distributors in operative contact with the guide rail, internal tubes, wicks extending upwardly from the bottom of said reservoir 70 into, down and through said internal tubes, a pocket provided in the under portion of said oiler, said wicks emerging from said tubes into said pocket and thence to the distributors, ports, drilled in the threaded portion of 75 said tubes, by means of which an increased saturation of said wicks may be had or heavier grades of oil may be used and means for concealing said ports whereby lighter grades of oil may be used.

4. An oiler for elevator guide rails, comprising a reservoir to be carried by the elevator, distributors slidably mounted in the lower part of said reservoir and beneath the lubricant, means for holding said distributors in operative contact with the guide rail, internal tubes, wicks extending upwardly 80 from the bottom of said reservoir into, down and through said internal tubes, a pocket provided in the under portion of said oiler, said wicks emerging from said tubes into said pocket and thence to the distributors, providing means for access of the wicks to the distributors and to allow an adjusting space for said internal tubes.

5. An oiler for elevator guide rails, comprising a reservoir to be carried by the elevator, distributors slidably mounted in the lower part of said reservoir and beneath the lubricant, means for holding said distributors in operative contact with the guide rail, internal tubes, wicks extending upwardly 90 from the bottom of said reservoir into, down and through said internal tubes, a pocket provided in the under portion of said oiler, said wicks emerging from said tubes into said pocket and thence to the distributors, said wicks being at all times concealed to prevent dust and dirt from clogging the pores thereof.

6. An oiler for elevator guide rails, comprising a reservoir to be carried by the elevator, distributors slidably mounted in the lower part of said reservoir and beneath the lubricant, means for holding said distributors in operative contact with the guide rail, internal tubes, wicks extending upwardly 100 from the bottom of said reservoir into, down and through said internal tubes, a pocket provided in the under portion of said oiler, said wicks emerging from said tubes into said pocket and thence to the distributors, said wicks being at all times concealed to prevent dust and dirt from clogging the pores thereof.

7. An oiler for elevator guide rails, comprising a reservoir to be carried by the elevator, distributors slidably mounted in the 115

lower part of said reservoir and beneath the lubricant, means for holding said distributers in operative contact with the guide rail, internal tubes, wicks extending upwardly 5 from the bottom of said reservoir into, down and through said internal tubes, a pocket provided in the under portion of said oiler, said wicks emerging from said tubes into said pocket and thence to the distributers, 10 said distributers being provided with a bridge wall having a sloping surface, the lower portion thereof terminating at the face of said distributers to permit the lubri-

cant to flow to the guide rail without interruption, said bridge wall providing a storage space for the lubricant when the elevator is not in motion and means to drain the lubricant from such storage space when the elevator is in motion. 15

In testimony whereof I affix my signature 20 in presence of two witnesses.

JOHN FRANKLIN MacINDOE.
